UNITED STATES PATENT OFFICE.

SAMUEL MODERN, OF NEW YORK, N. Y.

SLEEPING DOLL.

1,268,753.

Specification of Letters Patent.

Patented June 4, 1918.

Application filed December 1, 1917. Serial No. 204,855.

To all whom it may concern:

Be it known that I, SAMUEL MODERN, a citizen of Austria-Hungary, and a resident of the city of New York, borough of Manhattan, in the county and State of New York, have invented a new and Improved Sleeping Doll, of which the following is a full, clear, and exact description.

My invention relates to dolls having gravitationally operable eyes. An object of the invention is to provide a simple and inexpensive arrangement which will permit a variation of the distance between the eyes to adjust the same to dolls of different sizes.

Another object of the invention is to provide a doll having movable eyes and a movable tongue operable by the same gravitational means which operates the eyes.

With the above and other objects in view, the nature of which will more fully appear as the description proceeds, the invention consists in the novel construction, combination and arrangement of parts as herein fully described, illustrated and claimed.

In the accompanying drawings, forming part of the application, similar characters of reference indicate corresponding parts in all the views.

Figure 1 is an elevation of a doll provided with an embodiment of my invention;

Fig. 2, a vertical section through the doll in side elevation;

Fig. 3, a front elevation of the movable eyes and mechanism for operating the same;

Fig. 4, a section on line 4—4, Fig. 3.

Referring to the drawings, 5 is the support for the eyes. It has lugs 6 rising therefrom in which stems 7 of the eyes 8 are adapted to bear. The support proper is to be secured within the doll by any suitable means. The eyes 8 are stamped out from a blank having a circular portion which is shaped into a hemisphere from the edge 45 of which the stem extends and which is shaped into a triangular tube, one of the stems forming a socket for the triangular-shaped stem of the cooperating eye. It therefore follows that one of the stems is smaller than the other and the two eyes may be adjusted to or from one another but prevented from turning relative to one another by the engagement of the triangular-shaped stems, the openings in the 55 lugs 6 being round so as to allow the stems 7 to turn therein.

The larger stem 7 engages a triangular-shaped opening in the end of a pendulum 9. The pendulum is preferably in the shape of a tapering blade, the opening for the stem 60 being formed in the narrower end and, preferably toward one corner. The narrower end is so cut that it is adapted to engage the supports and thereby limit the swinging movement of the pendulum and prevent the 65 free end of same from striking the top of the doll's head. The weight of the pendulum may be varied by adding washers 10 at its free end. In forming the triangular opening in the pendulum for the stem 7, the material is deflected to form flanges 11 so as to increase the bearing surface of the opening for the stem.

The movement of the pendulum also actuates a tongue 12 which has within the doll 75 a yoke 13 pivotally connected to the pendulum. In the vertical position of the doll the pendulum brings the tongue out of the mouth of the doll. In placing the doll in the horizontal position the movement of the 80 pendulum draws the tongue inwardly.

In mounting the eyes, the pendulum 9 is first slipped on the larger stem 7; then the smaller stem 7 is fitted into the larger stem 7. The engagement of the two stems is with 85 sufficient friction so that an effort is required to move the eyes to or from one another, thus, the eyes are prevented from accidental displacement after they are mounted within the doll. The proper distance between the eyes is determined before the support 90 5 is cemented within the doll.

I claim:

1. In a sleeping doll, an eye support, eyes each having a lateral stem, said stems having a sliding engagement to prevent their turning relative to one another, said stems bearing in said support, and a pendulum constrained to revolve with said stems.

2. In a sleeping doll, an eye support, eyes each having a lateral triangularly-shaped stem, one of said stems being tubular to accommodate the other stem, whereby the two eyes may be moved to or from one another but prevented from turning, said stems being mounted to turn in the support, and a pendulum having a triangular opening for engaging one of the stems, whereby said eyes are moved in the support when the pendulum is displaced.

3. In a sleeping doll, an eye support, eyes each in the shape of a hemisphere having a

lateral, substantially triangular stem at the edge, one of said stems being tubular to receive the other stem whereby the two eyes may be moved to or from one another but are prevented from turning, said support having a round opening for said triangular stems wherein the same are mounted to turn, and a pendulum having a triangular opening for engaging the triangular stem, said opening in the pendulum being flanged by

the depression of the material to form the triangular openings for the stem.

4. In a sleeping doll, in combination, an eye support, eyes revolvably mounted on said support, a pendulum for moving said eyes, and a tongue in pivotal connection with the pendulum and adapted to be drawn in when the doll is placed in a substantially horizontal position.

SAMUEL MODERN.
